UNITED STATES PATENT OFFICE

2,165,141

RAM

Fred W. Hecht, Clairton, Pa.

Application February 23, 1937, Serial No. 127,247

7 Claims. (Cl. 214—23)

This invention relates to rams and, while not limited thereto, relates more particularly to rams for use with by-product coke ovens and the like.

Heretofore, rams such as are used to push coke from by-product coke ovens have been rectangular, or box-like, in cross-section. Oftentimes the rams are heated to a high temperature in the coke ovens and, when removed therefrom, their sides frequently were cooled at an uneven rate due to atmospheric conditions. This uneven cooling of the rams caused them to warp and crack so that they required frequent maintenance work. Even though the rams were frequently repaired, their lives were quite short and they tended to bind in the ovens.

One of the objects of this invention is to overcome the above and other disadvantages of known types of rams and to provide a sturdy ram which has a long life under sudden and repeated changes in temperature.

The above and further objects will be made apparent by referring to the following description and the accompanying drawing, in which:

Figure 1 is a plan of the device of the invention, 25 with the center portion thereof being removed;

Figure 2 is an elevation of the device of Figure 1;

Figure 3 is an enlarged elevation of the front end of the device of Figure 1;

Figure 4 is a transverse sectional elevation on line IV—IV of Figure 3; and,

Figure 5 is a transverse sectional elevation on line V—V of Figure 3.

Referring more particularly to the drawing, the numeral 2 indicates generally a ram which includes an open truss unit 4. The open truss unit 4 contains an upper cover-plate 6 and a lower cover-plate 8, both of which extend the length thereof. The cover-plates 6 and 8 are provided 35 with channels 10 and 11, respectively, which are secured to the adjacent surfaces thereof, as shown in the accompanying drawing.

In order to hold the cover-plates in spaced relation and form the open truss unit 4, reenforcing means, such as a plurality of channels 12, are secured between the upper cover-plate 6 and the lower cover-plate 8 to form a standard lacing. The ends of the channels 12 contact and are secured to each other as well as one of the channels 50 10 and 11. The rear portion of the open truss unit 4 is braced by several members 14 which extend perpendicularly between the channels 10 and 11 and which have a brace 16 therebetween.

One of the members 14 contacts and braces the 55 channel 12 nearest the rear of the open truss unit

4. A bar 18, or a similar device, protrudes from the open truss unit 4 adjacent the rear thereof to serve as a stop for the open truss unit 4.

A plurality of inverted V-shaped plates 20 may be carried by portions of the upper surface of the 5 channel 11. The legs of the plates 20 are secured to the channel 11 so that the plates 20 form slanted upper surfaces for portions of the channel 10. The plates 20 prevent any objects from remaining on the upper surface of the channel 11. 10

The ram 2 is provided with a short section of H-beam 22, or a similar device, at the front end thereof for the purpose of stiffening this end and causing the distribution of resisting forces 15 throughout the ram when it is in operation. Strengthening means, such as filler tubes 24, are mounted between the flanges of the H-beam 22 to give the beam additional strength.

A plurality of holes 26 are formed in the upper cover-plate 6 and lower cover-plate 8 to facilitate 20 the fastening of driving means to the ram.

Angles 28 are carried by portions of the open truss unit 4 to aid in the positioning thereof.

A welded construction is contemplated for the ram 2 in order to give it maximum strength with 25 a minimum of weight. The welded construction aids in spacing the channels 12 and allows substantially open portions to be formed between the upper cover-plate 6 and the lower cover-plate 8. These open portions are desirable in that they 30 permit substantially the entire structure of the open truss unit 4 to be subjected to the same atmospheric conditions simultaneously. This tends to insure uniform cooling of the open truss unit 4 and allows the ram to be repeatedly subjected to 35 severe and sudden changes in temperature.

While I have shown and described one specific embodiment of the present invention, it will be understood that I do not wish to be limited exactly thereto since various modifications may be 40 made without departing from the scope of the invention as defined by the following claims.

I claim:

1. A ram comprising an upper cover-plate, a lower cover-plate, a plurality of lacing members 45 extending diagonally between said cover-plates and forming a unit therewith whereby a substantially open space is formed between said cover-plates, V-shaped plates carried by portions of the upper surface of said lower cover-plate to form 50 slanted surfaces therefor, and means adapted to distribute and transmit large compressive forces associated with one end of said unit.

2. A ram comprising a pair of longitudinally 55 extending spaced-apart channel members, means

- extending between said members for securely holding them in spaced relation so as to provide an open truss unit, an H-beam member arranged at one end of said channel members with one of its flanges positioned against the ends thereof, said H-beam member having a plurality of filler tubes perpendicularly arranged between its flanges, and reenforcing means arranged between the channel members at the opposite end thereof.
- 5 3. A ram comprising a pair of longitudinally extending channel members spaced from each other with their channel portions oppositely disposed, a plurality of lacing members extending diagonally between said members for securely holding them in spaced relation so as to provide an open truss unit, a longitudinally extending cover-plate enclosing each of the channel portions of said channel members, said plates extending beyond the ends of said channel members
- 10 at least at one end of said truss unit, and a reinforced H-beam member positioned between the extending portions of said cover-plates against the ends of said channel members so as to distribute and transmit large compressive forces
- 15 exerted thereon throughout the ram.
- 15 4. The combination defined in claim 3, wherein the reenforcing means comprises an H-beam member having a plurality of filler tubes arranged between its flanges, said H-beam member arranged between the cover-plates with one of its flanges positioned against the ends of the channel members.
- 20 5. A ram comprising a pair of longitudinally extending channel members spaced from each other with their channel portions oppositely disposed, a plurality of lacing members extending diagonally between said members for securely holding them in spaced relation so as to provide an open truss unit, a longitudinally extending cover-plate enclosing each of the channel portions of said channel members, said plates extending beyond the ends of said channel members at one end of said truss unit, an H-beam member arranged between the extending portions
- 25 of said cover-plates with one of its flanges positioned against the ends of said channel members,

said H-beam member having a plurality of filler tubes perpendicularly arranged between the flanges thereof, and a pair of reenforcing members perpendicularly arranged between the channel members at the opposite end of said truss unit, said reenforcing members being spaced apart in parallel relation with a reenforcing member arranged therebetween.

6. A ram comprising a pair of longitudinally extending channel members spaced from each other with their channel portions oppositely disposed, a plurality of lacing members extending diagonally between said members for securely holding them in spaced relation so as to provide an open truss unit, a longitudinally extending cover-plate enclosing each of the channel portions of said channel members, said plates extending beyond the ends of said channel members at least at one end of said truss unit, and an H-beam member positioned between the extending portions of the cover-plates with one of its flanges positioned against the ends of the channel members, said H-beam member having a plurality of filler tubes arranged between its flanges and adapted to distribute and transmit large compressive forces exerted thereon throughout the ram.

7. A ram comprising a pair of longitudinally extending channel members spaced from each other with their channel portions oppositely disposed, a plurality of lacing members extending between said channel members for securely holding them in spaced relation so as to provide an open truss unit, a longitudinally extending cover-plate enclosing each of the channel members, said plates extending beyond the ends of the channel members at least at one end of said truss unit and a reenforcing structural member having a plurality of reenforcing filler tubes associated therewith, said structural member together with the filler tubes positioned between the extending portions of said cover-plates against the ends of said channel members so as to distribute and transmit large compressive forces exerted thereon throughout the ram.

45 FRED W. HECHT.
